UNITED STATES PATENT OFFICE

106,797

DESIGN FOR AN OVAL RELISH TRAY OR SIMILAR ARTICLE

Curtis B. Ilgenfritz and Edwin E. Slick, Jr., Pittsburgh, Pa., assignors to United States Glass Company, Pittsburgh, Pa., a corporation of Pennsylvania

Application June 22, 1937, Serial No. 69,988

Term of patent 7 years

To all whom it may concern:

Be it known that we, Curtis B. Ilgenfritz and Edwin E. Slick, Jr., citizens of the United States, residing at Pittsburgh, county of Allegheny, in the State of Pennsylvania, have invented a new, original and ornamental Design for an Oval Relish Tray or Similar Article, of which the following is a specification, reference being had to the accompanying drawing, forming a part thereof, in which

We claim:

The ornamental design for an oval relish tray or similar article, substantially as shown.

EDWIN E. SLICK, JR.
CURTIS B. ILGENFRITZ.
